US00D831680S

(12) **United States Design Patent** (10) **Patent No.:** **US D831,680 S**
(45) **Date of Patent:** **** Oct. 23, 2018**

(54) **DISPLAY SCREEN OR PORTION THEREOF
WITH GRAPHICAL USER INTERFACE**

(71) Applicant: **Lutron Electronics Co., Inc.**,
Coopersburg, PA (US)

(72) Inventors: **Erica L. Clymer**, Northampton, PA
(US); **Shannon M. Sullivan**,
Coopersburg, PA (US)

(73) Assignee: **Lutron Electronics Co., Inc.**,
Coopersburg, PA (US)

(**) Term: **15 Years**

(21) Appl. No.: **29/633,009**

(22) Filed: **Jan. 11, 2018**

Related U.S. Application Data

(63) Continuation of application No. 29/609,144, filed on Jun. 28, 2017, now Pat. No. Des. 810,776, which is a continuation of application No. 29/564,590, filed on May 13, 2016, now Pat. No. Des. 794,064.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
